Design No. 12,555, dated November 1, 1881.

UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,555, dated November 1, 1881.

Application filed August 25, 1881. Term of patent 3½ years.

To all whom it may concern:

Be it known that I, EDUARD LEISSNÈR, of New York, in the county and State of New York, have invented a new and Improved Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a carpet bearing my new design.

A vine-like stem, D, winds through the entire ornament, and has nearly circular flowers d, and between them, on stems i, peculiar-shaped leaves f. The stems that carry the flowers d

have at their lower parts also triangular leaves h, with undulating edges. Rosettes e, of peculiar outline, consisting of five rays around a circle, and with leaf-like ornaments between the rays, decorate the spaces between the stems, as shown.

I claim—

1. The design for wall-paper, consisting of the rosette e, substantially as shown. 25
2. The design for wall-paper, consisting of the stem D, flower d, leaf h, stem i, leaf f, and rosette e, substantially as shown.

EDUARD LEISSNÈR.
